COIN DETECTING APPARATUS

John F. Lindberg, Chicago, Ill.

Application February 23, 1937, Serial No. 127,003

12 Claims. (Cl. 194—193)

This invention relates to a coin detector.

Coin controlled machines in use today possess generally the disadvantage of being susceptible to operation by crudely and cheaply made slugs or fake coins inserted by unscrupulous persons. The owners or proprietors of such machines have suffered considerable losses in revenue because of the increasingly large numbers of such slugs fraudulently employed, to obtain goods or services without payment. This "cheating" of coin-controlled machines has, in certain sections of the country, and particularly in the larger cities, become a more or less "popular pastime" or form of amusement to otherwise honest and scrupulous citizens. It has become so prevalent in certain sections that the telephone companies have been compelled to place on the coin receptacle of each pay station box a member fitted with various prongs, slots and the like, which prevent the insertion of any device save a complementally shaped and slotted slug which can only be purchased from an attendant or from a clerk in the store in which the station is located. The successful operation of a system such as this requires that the fitted members and slugs for each pay station, or group of stations at one location, be different from the fitted members and slugs for all other stations or groups in that vicinity. The cost of manufacturing and handling the necessarily large number of different receptacles and slugs increases the cost of the service to the company. The necessity of obtaining slugs and the difficulties attendant upon an attempt to insert one of those slugs in its receptacle are sources of considerable annoyance to and loss of time by the customer. Previous attempts to design means to select slugs or spurious checks from coins for the purpose of preventing the fraudulent operation of coin-controlled machines have resulted in mechanisms which, because of their complexity, their costliness and their relative inefficiency, have failed to solve commercially the problem of fraud prevention. In order to meet this problem, it is essential that the coin detector mechanism be of relatively simple construction and of an efficiency such that the savings effected thereby are more than sufficient to sustain its cost of manufacture and installation.

It is accordingly an object of this invention to provide in coin controlled mechanism or machines, a simplified, efficient and highly sensitive coin detector which rejects slugs of every description and passes only coins of the proper size and weight to the control mechanism, there-

by preventing such fraudulent manipulation or "cheating" of the machine or mechanism.

It is a further object of this invention to provide a simplified and relatively inexpensive coin detector which is capable of sorting coins from slugs of greater or lesser diameter, rejecting the slugs, and passing the coins to a mechanism intended to be operated by those coins.

It is another object of applicant's invention to provide a compact and simplified coin detector which is capable of sorting coins from slugs of greater or lesser thickness, rejecting the slugs and passing the coins.

It is a further object of this invention to provide a peculiarly simple and efficient coin detector which is capable of sorting coins from slugs of greater or lesser weight, rejecting the slugs, and passing the coins to a coin control mechanism to be operated thereby.

It is a further object of this invention to provide a highly simplified and efficient coin detector which is capable of separating coins from slugs which differ from normal coins in diameter, thickness or weight, rejecting the slugs and passing the coins to the coin operated mechanism.

It has heretofore been proposed to weigh tokens or checks by means of scales or balances across which the token or check rolls or bounces during the weighing operation and from which it is directed along one of several paths depending on the deflection of the scale. In use it has been found that such means are not sufficiently sensitive to make a practical separation of tokens according to weight because the percentage of slugs passed by such means is relatively high. Applicant has found that the rolling of the token on the weighing means during the weighing operation materially interferes with the accuracy of the operation.

40 A further object of applicant's invention, therefore, is to provide a token or check weight-determining and selecting mechanism, which is more sensitive than any heretofore known and one in which the token remains stationary relative to the weighing means during the weighing operation.

Another object of the invention is to provide in a coin detector, an auxiliary weight-determining and selecting mechanism for rejecting tokens of a weight beyond a certain narrow weight-range and for delivering the tokens within that narrow weight-range to a main weight-determining and selecting mechanism of substantially greater sensitivity, whereby all remaining tokens which differ in weight from the weight of the

true coin by any amount in excess of the standard weight-tolerance of coins are absolutely and positively rejected.

A further object of the invention is to provide, in a mechanism for weighing and directing tokens, an extremely sensitive pendulum directing the tokens along different predetermined paths in accordance with the amplitude of oscillation of the pendulum.

Another object of the invention is to provide, in a coin detector having a weight determining and selecting means, size measuring and selecting means for receiving the operating tokens and for preventing passage of a token of a size different from a true coin to the weight determining means.

Another object of the invention is to provide, in a coin detector having an operating handle, means responsive to the size of the token inserted in the detector for clamping the handle against movement and preventing the insertion of an over or under sized token.

Another object of the invention is to provide, in a coin detector having an operating handle, means responsive to the size of the token inserted in the detector for clamping the handle against movement in a direction to insert the token into the detector, but allowing movement of the handle in the opposite direction to deliver an over or under sized token to the reject channel for return to the operator.

Further objects and advantages will be apparent from the following detailed description of one illustrative embodiment of the invention when considered with the accompanying drawings wherein:

Fig. 1 is a view in perspective of the coin detector embodying the applicant's invention;

Fig. 2 is a view in vertical elevation showing the side of the coin detector opposite from that shown in Fig. 1;

Fig. 3 is a vertical elevation of the coin detector with one cover plate removed;

Fig. 4 is a detailed view showing the operation of a portion of the mechanism;

Fig. 5 is a perspective exploded view of a portion of the mechanism;

Fig. 6 is a vertical elevation of the upper part of the mechanism with a cover plate removed;

Fig. 7 is a fragmentary horizontal section taken along the line 1—1 of Fig. 1;

Fig. 8 is a view similar to Fig. 7 with a token of a smaller size;

Fig. 9 is a view similar to Fig. 7, but with a token of larger size;

Fig. 10 is a vertical section taken along the line 10—10 of Fig. 7;

Fig. 11 is a view similar to Fig. 6, but with a token of smaller size;

Fig. 12 and Fig. 13 are vertical elevations showing the operation of a portion of the mechanism;

Fig. 14 is a horizontal section similar to Fig. 7;

Fig. 15 is a fragmentary view in elevation of a portion of the mechanism;

Fig. 16 is a fragmentary vertical section taken along the line 16—16 of Fig. 15;

Fig. 17 is a view in exploded perspective of certain elements of Figs. 15 and 16;

Fig. 18 is a fragmentary vertical section taken along the line 18—18 of Fig. 3;

Figs. 19 to 24 are detailed views in elevation showing the operation of a portion of the mechanism, and

Figs. 25, 26 and 27 are diagrammatic sketches

illustrating the operating principles of a portion of the mechanism.

As shown in the drawings, the coin detector comprises a frame 2 having a body portion 4, a front face 6, and an upper face 8 formed by flanges extending oppositely from the body 4. One side of the body 4 is milled to provide a guideway 10, a recess 12 and coin directing channels 14, 16 and 18. A plurality of operating levers or slides 20, 22, 24 and 26 are slidably mounted in the guideway 10, and the levers 22, 24 and 26 extend outwardly therefrom and are supported in an L-shaped bracket 28 formed integrally with the front face 6 of the frame. A cover plate 30, secured to one side of the body 4, has a forwardly projecting portion 32 passing through an aperture 34 in the face plate 6, and secured to the bracket 28, to form therewith a housing for the outer end of the operating levers 22, 24 and 26. The lever 26 is the main operating lever and carries at its outer end a laterally extending portion 36 forming a handle by which the lever 26 is to be operated. The lever 22 is riveted to the lever 24 and in its outer position extends from the outer face of the bracket 28 inwardly a sufficient distance to engage the forward edge of a coin inserted between the projecting portion 32 of the cover plate 30 and the lever 24; the portion 32, the bracket 28 and the levers 24 and 26 having semi-circular grooves in their upward edges to permit the ready insertion of the coin. The lever 20 is mounted in the guideway 10 in alignment with the lever 22 and has a lost motion connection to the lever 24. This lost motion connection comprises a pair of lugs 38 and 40 (Fig. 7) formed integrally with and projecting outwardly from the levers 20 and 24 adjacent their rear edges. The lug 40 extends through a slot 42 (Fig. 5) in the rear edge of the lever 20 and is connected to the lug 38 by a bolt 44 (Fig. 7) passing through aligned apertures in the respective lugs. The bolt 44 is adjusted to permit the levers 22 and 24 to move rearwardly relative to the lever 20 so that a coin of the proper diameter will be clamped between the levers 20 and 22, but a token or slug of lesser diameter will not engage the forward edge of the lever 20. A spring steel member 46, of V-shaped configuration, is mounted in the recess 12 above the lever 20, and this spring bears at its upper end against the upper edge of the recess and at its lower edge against the lever 20 for the purpose of preventing movement of the lever 20 during the initial movement of the levers 22 and 24. Lever 24 has an overload release connection to the main operating lever 26. This overload release connection comprises a member 48 (Fig. 12) which has a base portion 50 riveted or otherwise secured to the lever 24 adjacent its rear edge, an arm 52 extending longitudinally of the lever 24 and an enlarged head 54. The head 54 has a semi-circular or elliptical aperture 56 in its outer edge. The lever 26 is provided at its rear end with inwardly extending flanges 58 for receiving therebetween the arm 52 of the member 48, and the head 54 of this member is received in a slot 60 formed in the lever 26 inwardly of the flanges 58. A second slot 62 of less width is formed in the lever 26 inwardly of the slot 60 and is connected thereto by beveled shoulders 64. A V-shaped fork 66 of spring steel has its head 68 spring-pressed into the aperture 56 of the member 48, and the tines of the fork are normally held apart by a spring 70 interposed therebetween. The outer ends of the tines

are provided with cam fingers 72 which normally engage the shoulders 64 and extend a slight distance into the slot 62.

A small lever 74 is mounted in the recess 12 in vertical alignment with the lever 20, and is provided with a semi-circular knurled portion 76, a nose 78, and a finger 80 directed oppositely from the nose 78. A pin 82 pivotally secures the lever 74 to the body 4, and it is to be noted that this pivot is eccentric to the semi-circular portion 76. An adjustable lever 84 (Fig. 2), pivoted to the outer face of the body 4, is provided with a finger 86 extending through a slot 88 in the body 4 and engaging the finger 80 of the lever 74 for the purpose of pre-setting the lever 74 so that the knurled portion 76 will engage the circumference of an over-size slug. The set screw 90, which passes through an arcuate slot in the lever 84 and threadedly engages the outer face of the body 4, provides means for locking the lever 84 in adjusted position.

On the side of the guideway 10 opposite to and in alignment with the lever 74, there is inserted a block 91 separating the channel 16 from the channel 14. This block 91 is provided with a knurled upper surface for engaging the periphery of the token and causing it to rotatively engage the semi-circular portion 76 of the eccentrically mounted lever 74.

To a bracket 92 (Fig. 7) carried by the plate 30 and in alignment with the lever or slide 20 is pivoted a lever 94. At its forward end the lever 94 is provided with a right angle finger 96 having a rearward curve or cam surface 98 for a purpose later to be described. The finger 96 passes through and normally rests in an aperture 100 in the cover plate 30. In the opposite end of the lever there is threaded a set screw 102 provided with a clamping nut 104 for retaining the set screw in adjusted position relative to the lever 94. A set screw 106, which has a rounded head 108 is threaded into the lever 94 between its pivot point and the finger 96. The usual clamping nut 110 secures the set screw in adjusted position. The set screws 102 and 106 extend through suitable apertures 114 and 112, respectively, in the cover plate 30 in position to engage the outer face of a coin or token upon rearward movement of the levers 22, 24 and 26.

Under certain conditions the set screw 102 must move inwardly of the outer edge of the lever or slide 20 and for this purpose the said lever or slide is provided with a longitudinal recess 116 (Figs. 4 and 9) in horizontal alignment with said set screw.

A leaf spring 118 of somewhat bowed configuration is seated in notches in the cover plate 30 and engages the inner side of the lever 94 to normally urge it in a counterclockwise direction as seen in Fig. 7.

The mechanism heretofore described constitutes a size determining and selector mechanism which operates to pass coins of the proper size and to reject slugs of larger or smaller size. The operation of this mechanism is as follows:

A coin or slug or other token having been inserted, the handle 36 is operated to move the lever 26 rearwardly. The motion of the lever 26 is transmitted through the shoulder 64, the fork 66 and the member 48 to the lever 24 and from the lever 24 to the lever 22 which is in engagement with the forward edge of the coin or slug.

If the token inserted is a coin of the proper diameter, the rear edge of the coin will engage the forward edge of the lever 20 just before the

lever 24 has moved rearwardly a sufficient distance to be connected to the lever 20 by the lugs 38 and 40 and the bolt 44. Since the movement of the lever 20 is resisted by the spring 46, the coin will be effectively clamped between the levers 20 and 22, and will thereafter be carried past the channel 16 and to the channel 14. When a coin reaches the channel 14, the spring 46 will drop below the upper surface of the slide 20 and engage its forward edge, as seen in Fig. 4. The spring 46 will then force the slide 20 rearwardly relative to the slide 24, taking up the remaining lost motion between said slides and freeing the token. The token then drops by gravity into the channel 14. It is to be noted in this connection that the forward half of the upper edge of the lever 20 is cut away to provide a recess into which the semi-circular portion 76 of the lever 74 normally projects, and to effect a decrease in the retarding force of the spring 46 after the coin has passed the channel 16.

If the token is of less diameter than the normal diameter of the proper coin, the lost motion between the levers 20 and 24 will be taken up before the rear end of the slug can contact the forward edge of the lever 20; therefore, as the levers 22, 24 and 26 move rearwardly, the slug will not be clamped between the levers 20 and 22, and will, on the action of gravity, drop into the reject channel 16.

If the token is of greater diameter than the normal diameter of the proper coin, it will be clamped between the levers 20 and 22, but before it reaches the channel 14 it will engage the knurled block 91 which will cause it to rotatively engage the semi-circular portion 76 of the eccentrically mounted lever 74. In rotating, the nose 78 of the lever 74 will engage the upper edge of its recess 12 (Fig. 12), causing the slug to be jammed against the knurled edge of the block 91 and preventing further inward movement of the levers and slug. In order to protect the apparatus against extraordinary forces which might be spitefully applied in an attempt to force a slug into the machine, the overload release connection between the main operating lever 26 and the lever 24 has been provided. If such a force is applied to the operating lever 26 and this force is in excess of the retarding force exerted by the fork 66 and spring 70, the tines of the fork will be forced inwardly under the camming action of the shoulders 64 and fingers 72, as shown in Fig. 13. The release of the fingers 72 from shoulders 64 will permit the lever 26 to move rearwardly relative to the lever 24 until the lugs or flanges 58 engage the plate 50. In this position of lever 26, the handle 36 will be in contact with the outer edges of the bracket 28 and the projecting portion 32 of the cover plate 30. Further inward movement of the lever 26 is, of course, impossible.

When the token is of the proper diameter, it will pass the reject channel 16, and will not engage the lever 74, but if it is either thinner or thicker than the normal coin it will not be fed to the channel 14. If it is thinner than the normal size coin, the set screw 106 may move inwardly so that the spring 118 rotates the lever 94 counterclockwise, as seen in Fig. 8, and projects the finger 96 into an aperture 120 (Fig. 8) in the slide 22 and further rearward movement of this slide is therefore prevented. The latching of slide 22 also serves to latch the slides 24 and 26. However, upon the application of an overloading force, the slide 26 can be moved relative to the slide 24 without affecting the locked condi-

tion of the slides 22 and 24 in the manner previously described. If the token is a coin of the proper thickness, the set screw 106 will hold the finger 96 of the lever 94 out of engagement with the aperture 120 and therefore the movement of the coin to the channel 14 is not prevented. If the token is a slug thicker than a normal coin, the set screw 106 will be moved outwardly rotating the lever 94 clockwise (Fig. 9), and causing the forward edge of the set screw 102 to pass into the slot 116 of the lever 20 and engage the forward edge of the slug. In this manner, the lever 22 and the lever 24 are again latched against further inward movement.

In all cases where the slug causes the locking of the operating mechanism against further inward movement, the slug may be fed to the reject channel 16 and the apparatus restored to normal operating condition by simply withdrawing the handle 36. For this purpose the lever 74 is eccentrically pivoted, the eccentric radius increasing from the nose 78 to the finger 80 (Fig. 12), and the leading edge of the aperture 120 (Fig. 8) is provided with a cam surface to co-act with the cam surface 98 of the finger 96.

On the side opposite the channels 14, 16 and 18, the body 4 is provided with an annular flange 122 (Figs. 2 and 18) forming, with a pair of cover plates 124 and 126, a housing for a weight-measuring or weight-determining mechanism 128. The weight-measuring or determining mechanism 128 comprises a shaft 130 (Fig. 18) which extends from the housing through an opening 131 in the body 4 and is mounted at its opposite ends on substantially frictionless pivots 132 and 134. The frictionless pivot 132 comprises a set screw threaded through the V-shaped cover plate 124, which, it will be noted is of substantially greater thickness than the cover plate 126 for the purpose of providing more substantial support for the pivot 132. This set screw is clamped in adjusted position by the usual lock nut 136 and the inner end of the set screw is beveled to form a substantially pin-point frictionless support for the shaft 130. The frictionless pivot 134 is similar to pivot 132 and comprises a set screw threaded through an arm 138 formed integrally with the body 4 and extending through an aperture in the cover plate 30 to permit access to the set screw for ready adjustment of the same.

On its outer end the shaft 130 carries a collar 140 in which are threaded screws 142 and 144 (Fig. 3), and these screws threadedly receive small weights 146 and 148. A coin receptacle 150 is secured to the other end of the shaft 130 and this receptacle comprises a pair of jaws 152 and 154 (Figs. 19 to 24), and an off-set portion 156. Pivoted on the off-set portion 156 is a disc 158. The disc 158 is provided with three annularly spaced lugs 160 having inwardly bent outer edges forming channels with the body of the disc for receiving a coin or slug from the channel 14. A pin 162 (Fig. 16) is secured to or formed on the disc 158 adjacent its periphery and between the free ends of the jaws 152 and 154. The pin is internally threaded as at 164 and has secured to its outer edge a notched disc 166. A lever 168 is secured to the pin shaft 164 for movement relative thereto by a screw 170, and the lever 168 has an annularly bent pawl 172 engaging in the notch of the disc 166 to limit the movement of the lever relative to the pin shaft. The lever 168 is substantially triangular in configuration and is enlarged at its lower pointed end to provide the weight necessary to retain the lever in a vertical

position and to retain the pawl 172 in contact with one of the edges of the notch in the disc 166.

A weighted lever 174 (Figs. 3 and 19) is pivotally mounted in the channel 14 and controls the delivery of tokens to the weight-measuring mechanism 128. The weighted lever is normally retained in the position shown in Fig. 3 by stop pin 176 and its movement in a clockwise direction is limited by a similar stop pin 178. Lever 174 directs the coin or slug onto the disc 158 and between the jaws 152 and 154, the outer surface of the disc 158 being aligned with the edge of the base of the channel 14, as best shown in Fig. 18. The channel 14 is separated from the channel 18 by a portion 180 of the body 4 and by a pawl 182 aligned with portion 180 and fixedly secured to the body 4 by a set screw 184. At its lower end the channel 14 is provided with an opening 186 extending through the base of the channel. The portion 180 and the pawl 182 extend upwardly and outwardly from the base of the channel and are so inclined as to direct any slug in the bottom of the channel 14 into the opening 186 (Fig. 3).

The channel 16 is separated from the channel 18 by a portion 188 of the body 4 upstanding from the base of the channel and by a pawl 190 secured to the body 4 by a set screw 192. The channel 16 terminates at its lower end in an opening 194 (Fig. 3) which extends through the base of the channel. The right hand surface of the pawl 190 is so curved as to direct any slug which engages that surface into the opening 194.

In the side of the body 4, opposite to the channels 14 and 16, there is cut a way or guide 196 (Fig. 18) terminating at one end in alignment with the opening 186, and registering at its other end with an opening 198 formed in the face plate 6, adjacent its lower edge (see Figs. 2 and 3). Through the opening 198 are returned all slugs or coins which are not of the proper diameter, thickness or weight as a normal operating coin.

A plurality of annularly spaced pins 200, 202 and 204 are secured to the body 4 and extend into the way or guide 196 in positions to engage the weighted lever 168, as shown in Figs. 21 to 24. A cover plate 206 (Fig. 18) closes the way 196, and this cover plate is secured to the body 4 in any convenient manner, and has a laterally extending flange 208 closing the bottom of the housing formed by the flange 122 and the cover plates 124 and 126.

In describing the operation of the size-determining mechanism, it was pointed out that a coin, or slug of the proper diameter and thickness would be delivered to the channel 14. The operation of the mechanism thereafter described in determining differences in weight between coins and slugs, and in delivering only coins of the proper weight to the mechanism to be controlled will now be described.

From the upper end of the channel 14, the coin or slug rolls down the inclined surface of said channel onto the weighted lever 174. If it is a substantially underweight slug, it attains a sufficient velocity in rolling down the channel 14 to pass over the weighted lever 174 before that lever can be rotated clockwise by the weight of the slug a sufficient distance to check its forward movement. If it is a coin of the proper weight, or a slug slightly underweight, or an overweight slug, its weight will be sufficient in relation to its velocity to rotate the lever 174 a sufficient angular distance to cause the forward movement of the coin to be checked, and to

reverse the direction of rotation of the coin. The coin or slug then rolls from the lever 174, while rotating in a clockwise direction as seen in Fig. 19, onto the disc 153, the periphery of the slug or coin engaging the lugs 160. Because the coin or slug is rotating in the clockwise direction, and because, in moving downwardly from the lever 174, it first engages the right hand one of the lugs 160, the disc 153 is rotated thereby in a clockwise direction relative to jaws 152 and 154, causing the left hand lug 160 (Figs. 19 and 20) to approach the outer end of the jaw 154 and to assume a position wherein it is spaced from that jaw by a distance less than the diameter of the slug or coin, as best shown in Fig. 21. The rotation of the disc 153 relative to the off-set portion 156 is limited by the pins 210 and 212 which engage opposite sides of the off-set portion 156.

The principle of operation of the weight measuring or determining mechanism 123 is that of a compound pendulum (Figs. 25 to 27), of which the coin receptacle 150 is one weight A, the members 142, 144, 146 and 148 forming another weight B, and pivots 132 and 134 forming the axis of oscillation C. As will be evident, the amplitude of oscillation of the compound pendulum A, C, B depends upon the relative weights of members A and B, and the length of pendulum arms A—C and C—B. Assuming constant length of the pendulum arms A—C, and C—B, it will be further evident that the greater the weight A in relation to the weight B, the greater will be the amplitude of oscillation of the pendulum and that similarly, the greater the weight B in relation to the weight A, the lesser will be the amplitude of oscillation. If the weight B be constant, the amplitude of oscillation of the pendulum will vary directly with the weight A. This is shown in Figs. 25, 26 and 27. In Fig. 25 the weight A represents the weight of the receptacle 150 when a coin of the proper weight has been inserted therein. It will be seen that the greater weight A will cause the pendulum to oscillate counterclockwise from the rest position D to the extreme position E when it will reverse its direction of oscillation and pass through a position such as F. If the pendulum were free to oscillate, it would gradually come to rest at some new neutral position wherein the weight A, times the lever arm A—C, was equal to the weight B times the lever arm B—C. In Fig. 26 the weight A represents the weight of the receptacle 150 plus that of a slug which is greater in weight than the weight of the proper coin. This weight is greater than the weight A of Fig. 25 and it will be seen by a comparison of these two figures, that the extreme position E' to which the pendulum will be moved under the action of the heavier weight A is angularly advanced from the extreme position E, and that the angle of oscillation is the greater in the case of the heavier weight of Fig. 26. In returning from the extreme position E', the pendulum will, of course, pass through a position F', which is a slightly greater angular distance from the neutral position D than is the extreme position E of Fig. 25.

In Fig. 27 the weight A represents the weight of the receptacle 150 when a slug of lesser weight than the weight of the proper coin is inserted therein. The extreme position E'' to which the pendulum will be moved under this circumstance, is, of course, retarded with respect to the extreme position E of Fig. 25. The amplitude of the oscillation of the pendulum with

the lesser weight A is, of course, less than the amplitude of oscillation of the pendulum of Fig. 25. In returning from the extreme position E'' the pendulum will pass through some intermediate position such as F''. The similar intermediate position F of Fig. 25, it is to be observed, is at a slightly greater angular distance from the normal neutral position D than is the extreme position E'' of Fig. 27.

It will be evident from a comparison of Figs. 25, 26 and 27 that the pendulum of Fig. 27 never occupies a position between the points F and E of Fig. 25, and that the pendulum of Fig. 25 never occupies a position between the points F' and E' of Fig. 26. Therefore, it will be apparent that if the heavier weight A of Fig. 26 is removed from the pendulum while the pendulum is passing between the positions F' and E', the heavier weight may be separated from the lighter weights; similarly, it will be evident that if the medium weight is removed from the pendulum while the pendulum is positioned between points F and E (Fig. 25), the medium weight may be separated from the lighter weight. In order that the means for removing the lighter weight does not also remove the heavier weights, it is necessary that this removal be accomplished on the backward swing of the pendulum, i. e., when the pendulum is moving clockwise from each of the positions E, E' and E'' to the positions F, F' and F''. This is the principle of applicant's weight-measuring mechanism 123.

The pin 204 is positioned to correspond to a position intermediate F', E' of Fig. 26; the pin 202 is placed to correspond to a position between F and E of Fig. 25, and the pin 200 is placed to correspond to a position above the position E'' of Fig. 27. The weighted lever 168, which has the last motion connection 166 and 172 to the disc 153, co-operates with the pins 200, 202 and 204 to release the tokens from the coin receptacle 150 only during the backward swing of the pendulum. For this purpose, the lever 168 is free to ratchet over the pins 200, 202 and 204 during the counterclockwise rotation of the coin receptacle, the pawl 172 moving freely in the notch of disc 153 from its normal position in engagement with the upper edge of the notch. Upon the return swing of the pendulum, the rear edge of the lever 168 will be engaged by one of the pins 200, 202 and 204 and the lever will be rotated counterclockwise, as seen in Figs. 15, and 21 to 24. The lever 168 will rotate the disc 153 counterclockwise and release the coin from the coin receptacle 150, as shown in Figs. 22, 23 and 24. If the token inserted into the coin receptacle 150 is a coin of the proper weight, the pendulum, of which this receptacle forms a part, will begin oscillation, and the coin receptacle 150 will be moved to the extreme position shown in Fig. 21, wherein the lever or dog 168 is between the pins 202 and 204. When the pendulum swings back from this extreme position, the dog 168 will be engaged by the pin 202 to release the coin from the coin receptacle in the manner previously described. This release takes place in such a predetermined relation to the pawls 182 and 180 that the coin is guided by said pawls into the channel 18, from which channel the coins may pass in the usual and conventional manner to the machine to be controlled by said coins.

If a slug heavier than the proper coin is fed to the coin receptacle, the pendulum, of which the coin receptacle is a part, will be swung to a position somewhat to the right of the position

shown in Fig. 23, and upon the backward swing from this extreme position, the dog 168 will be engaged and rotated by pin 204 to release the heavier slug from the coin receptacle. The heavier slug will be guided by the right hand surface (Fig. 3) of the pawl 190, and by the portion 186 of the body 4 into the aperture 194 at the bottom of the channel 16. From the aperture 194 the slug will pass down the way or guide 196 and out of the opening 198.

If the token is lighter in weight than the proper coin, the coin receptacle will be moved to an extreme position wherein the dog 168 is somewhere between the pins 200 and 202 (Fig. 24). Upon backward swing of the coin receptacle, the dog will be engaged by the pin 200 to release the coin, which then falls down the inclined surface of the pawl 182 and the portion 180 of the body 4 into the opening 186, and from the opening 186 it passes down the way 196 and out of the opening 198.

It will be apparent from the foregoing description that the applicant has provided an especially effective coin detector for rejecting slugs of every description and passing only coins of the proper size and weight to a coin control mechanism, thereby preventing fraudulent manipulation or "cheating" of the coin controlled machine.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. In a coin detector, token receiving oscillatory means, the amplitude of oscillation of which is determined by the weight of the token, means operable by a token, in moving onto said oscillatory means, for clamping the token to the oscillatory means, means positioned at spaced points along the path of movement of said oscillatory means for operating said clamping means to release tokens at said spaced points in accordance with the weight of said tokens, and means for passing from the oscillatory means tokens of the proper weight in one direction and rejecting tokens of different weights in another direction.

2. In a coin detector, means for providing a first channel for passing tokens of a predetermined weight, and a second channel spaced from the first for returning tokens of different weights, oscillatory means for receiving tokens and operable by said tokens arcuate distances which vary in accordance with the weights of the tokens, means operable by the tokens for clamping the same to said oscillatory means, means positioned at a predetermined spaced point along the arc of movement of said oscillatory means for operating said clamping means to release a token of a predetermined weight from said oscillatory means and direct the same to said first channel, and means positioned at other predetermined spaced points along the arc of movement of said oscillatory means for operating said clamping means to release tokens of weights differing from said predetermined weight and direct the same to said returning channel.

3. In a coin detector, an operating channel and a rejecting channel and weighing means adapted to receive tokens for directing the same into said channels in accordance with their respective weights, said weighing means comprising

ing a pendulum having a token receptacle, means operable by a token for clamping the same in said receptacle, means carried by said clamping means and operable upon backward oscillation of the pendulum to release the token from said token receptacle, means positioned at a predetermined spaced point along an arc of movement of said pendulum for operating said releasing means to direct a token of a predetermined weight into said operating channel, and means at other predetermined spaced points along said arc of movement of said pendulum for operating said releasing means to direct tokens of greater and less weight into said rejecting channel.

4. In a coin detector, token directing means providing an operating channel and a rejecting channel, a pendulum having a token receptacle, clamping means mounted in said receptacle for movement relative to said pendulum, said clamping means being operable by a token for clamping the same in said receptacle, releasing means carried by said clamping means and operable upon backward oscillation of the pendulum to release the token from the token receptacle, said releasable means being mounted on said clamping means for movement relative thereto upon forward oscillation of the pendulum, means positioned at a predetermined spaced point along an arc of movement of said pendulum for operating said releasing means to direct a token of a predetermined weight into said operating channel and means at other predetermined spaced points along said arc of movement of said pendulum for operating said releasing means to direct tokens of greater and less weight into said rejecting channel.

5. In a coin detector, token directing means providing a receiving channel, an operating channel and a rejecting channel, a pendulum having a token receptacle, a counter-weighted lever between the receiving channel and a portion of the rejecting channel, said counter-weighted lever having a surface aligned with the receiving channel across which surface tokens outside a predetermined weight range pass to the rejecting channel, said counter-weighted lever being disposed above the pendulum and pivotal under the weight of a token within the predetermined weight range to cause such token to roll in a predetermined direction of rotation into the token receptacle, means pivotally mounted on the pendulum and pivoted relative to the pendulum by the rolling token to clamp the token to the pendulum, means positioned at spaced points along an arc of movement of said pendulum for operating said clamping means to release tokens at said spaced points in accordance with the weight of said tokens, means for receiving tokens of a predetermined weight from said pendulum for directing the same to said operating channel, and means receiving tokens of weights differing from said predetermined weight for directing said tokens to said rejecting channel.

6. In a coin detector, a first channel for passing tokens of a predetermined weight, a second channel for rejecting tokens of different weights, a pendulum having an opening facing outwardly to form a token receptacle, means for causing tokens to roll into said receptacle, a member rotatably mounted on said pendulum and having an annular token receiving channel within said opening, an edge of said channel being disposed within said opening to engage the rim of the token rolling into the receptacle to cause rota-

tion of said member relative to the pendulum whereby a portion of the channel closes the mouth of the opening forming the token receptacle to clamp the token in the receptacle, means positioned at a predetermined point along the arc of movement of said pendulum for rotating said member relative to the pendulum to withdraw said portion of the channel from the mouth of the token receptacle, whereby to release a token of predetermined weight from said pendulum and direct the same to said first channel, and means positioned at other predetermined points spaced from the first point along the arc of movement of said pendulum for rotating said member relative to the pendulum to withdraw said portion of the channel from the mouth of the token receptacle whereby to release tokens of weights differing from said predetermined weight and direct the same to said second channel.

7. In a coin detector, a first channel for passing tokens of a predetermined weight, a second channel for rejecting tokens of different weights, a pendulum having an opening facing outwardly to form a token receptacle, means for causing tokens to roll into said receptacle, a member rotatably mounted on said pendulum and having an annular token receiving channel within said opening, an edge of said channel being disposed within said opening to engage the rim of the token rolling into the receptacle to cause rotation of said member relative to the pendulum whereby a portion of the channel closes the mouth of the opening forming the token receptacle to clamp the token in the receptacle, a dog carried by said rotary member and operable upon backward oscillation of the pendulum to rotate said member to withdraw the portion of the channel from the mouth of the opening formed in the token receptacle, said dog being shiftably mounted on said rotary member for movement relative thereto upon forward oscillation of the pendulum, means positioned at a predetermined point along an arc of movement of said pendulum for engaging and operating said dog to rotate said rotary member whereby to release a token of a predetermined weight from said pendulum and direct the same into said first channel, and means at other predetermined points spaced along the arc of movement of said pendulum for engaging and operating said dog to rotate said member whereby to release tokens of greater and less weight from said pendulum and direct said tokens into said second channel.

8. In a coin detector, a counterweighted lever, means causing received tokens to roll by gravity onto said counterweighted lever, the counterweighting of said lever being such as to permit tokens differing a substantial amount from a predetermined weight range to pass over said lever and to cause pivotal movement of the lever upon receipt of tokens within the predetermined weight range whereby to cause the latter tokens to roll therefrom in a given direction of rotation and oppositely to the tokens not within the predetermined weight range, an oscillatory member positioned to receive tokens within the predetermined weight range from said counterweighted lever and operable by said tokens arcuate distances which vary according to the weights of the tokens, means rotatably mounted on the oscillatory member for clamping the same to said oscillatory member, means positioned at a predetermined

spaced point along the arc of movement of said oscillatory member operating said clamping means to release and pass a token of predetermined weight from said oscillatory member, and means positioned at other predetermined spaced points along the arc of movement of said oscillatory member for operating said clamping means to release and reject tokens differing from said predetermined weight.

10. In a coin detector, an oscillatory lever, the amplitude of oscillation of which is determined by the weight of a token, a token receptacle shiftably mounted on said oscillatory lever and having means to engage a token as it moves into said receptacle to clamp the token to the oscillatory lever, means positioned at spaced points along the path of movement of said oscillatory lever for operating said clamping means upon backward oscillation of said lever to release tokens at the said spaced points in accordance with the weights of said tokens, and means for passing from said oscillatory lever tokens of the proper weight in one direction and means for directing tokens of different weights in another direction.

10. In a coin detector, means for receiving and causing tokens to roll by gravity along a predetermined path, a counterweighted lever in said path to receive the rolling tokens, the counterweighting of said lever being such as to allow tokens of a weight substantially less than a predetermined standard to pass over the lever and to cause downward pivoting of the counterweighted lever under tokens more closely approximating the standard weight whereby to cause the last mentioned tokens to roll downwardly from the counterweighted lever, an oscillatory lever having a token receptacle in position to receive tokens rolling downwardly from the counterweighted lever upon pivoting of said counterweighted lever, said oscillatory lever being operable by said tokens arcuate distances which vary in accordance with the weights of the tokens, means shiftably mounted on the oscillatory lever and operable by a rolling token for clamping the same in said receptacle, means positioned at a predetermined spaced point along the arc of movement of said oscillatory lever for operating said clamping means upon backward oscillation of said oscillatory lever to release and pass a standard weight token from said token receptacle, and means positioned at other predetermined spaced points along the arc of movement of said oscillatory lever for operating said clamping means upon backward oscillation of said oscillatory lever to release and reject tokens of weights differing slightly from said predetermined weight.

11. In a coin detector, token directing means providing a receiving channel, an operating channel and a rejecting channel, a pendulum having a token receptacle, a counter-weighted lever between the receiving channel and a portion of the rejecting channel, said counter-weighted lever having a surface aligned with the receiving channel across which surface tokens outside a predetermined weight range pass to the rejecting channel, said counter-weighted lever being disposed above the pendulum and pivotal under the weight of a token within the predetermined weight range to cause upon pivoting of the lever such token to roll in a predetermined direction of rotation into the token receptacle, means pivotally mounted on the pendulum and pivoted relative to the pendulum by the rolling token

to clamp the token to the pendulum, means positioned at spaced points along an arc of movement of said pendulum for operating said clamping means upon backward oscillation of said pendulum to release tokens at said spaced points in accordance with the weight of said tokens, means for receiving tokens of a predetermined weight from said pendulum for directing the same to said operating channel, and means receiving tokens of weights differing from said predetermined weight for directing said tokens to said rejecting channel.

12. In a coin detector, a first channel for passing tokens of a predetermined weight, a second channel for rejecting tokens of different weights, a pendulum having an opening facing outwardly to form a token receptacle, means for causing tokens to roll into said receptacle, a member rotatably mounted on said pendulum and having an annular token receiving channel within said opening, an edge of said channel being disposed within said opening to engage the rim of the token rolling into the receptacle to cause

5 rotation of said member relative to the pendulum whereby a portion of the channel closes the mouth of the opening forming the token receptacle to clamp the token in the receptacle, means positioned at a predetermined point along the arc of movement of said pendulum for rotating said member relative to the pendulum upon backward oscillation of the pendulum to withdraw said portion of the channel from the mouth of the token receptacle, whereby to release a token of predetermined weight from said pendulum and direct the same to said first channel, and means positioned at other predetermined points spaced from the first point along the arc of movement of said pendulum for rotating said member relative to the pendulum upon backward oscillation of the pendulum to withdraw said portion of the channel from the mouth of the token receptacle whereby to release tokens of weights differing from said predetermined weight and direct the same to said second channel.
